UNITED STATES PATENT OFFICE.

FRANK FORAMA, OF WASHINGTON, DISTRICT OF COLUMBIA.

HEEL-PLATE.

1,204,969.

Specification of Letters Patent.

Patented Nov. 14, 1916.

Application filed October 19, 1915. Serial No. 56,756.

To all whom it may concern:

Be it known that I, FRANK FORAMA, a subject of the King of Italy, residing at Washington, District of Columbia, have invented 5 certain new and useful Improvements in Heel-Plates; and I do hereby declare the following to be a full, clear, and exact description of the invention, such as will enable others skilled in the art to which it applies to make and use the same.

10 The invention relates to improvements in heel plates for shoes.

The object of the present invention is to improve the construction of heel plates for 15 shoes and to provide a simple, inexpensive and efficient heel plate of strong and durable construction adapted to be readily applied to various styles and grades of shoes and capable of being firmly secured to the same 20 and of engaging and interlocking with the lift of the heels.

With these and other objects in view the invention consists in the construction and 25 novel combination and arrangement of parts hereinafter fully described, illustrated in the accompanying drawings and pointed out in the claim hereto appended, it being understood that various changes in the form, proportion and minor details of construction 30 may be resorted to without departing from the spirit or sacrificing any of the advantages of the invention.

In the drawing Figure 1 is a perspective view of a heel plate constructed in accordance with this invention, Fig. 2 is a sectional view of a portion of a heel illustrating the arrangement of the heel plate shown 35 in Fig. 1.

Like numerals of reference designate corresponding parts in the several figures of 40 the drawing.

In the accompanying drawing in which is illustrated the preferred embodiment of the invention, the heel plate comprises a 45 body portion 1 having flat upper and lower faces 2 and 3 and designed to be secured to a heel 4 with its lower face 3 in flush relation with the tread of the heel and the said lower face 3 is preferably roughened as 50 shown to prevent the wearer of the shoe from slipping. The body portion which is substantially oblong has curved inner and outer edges 5 and 6, the outer edge being convex and the inner edge being concaved 55 and the convex outer edge being adapted to conform to the configuration of a heel.

The body portion 1 of the heel plate is provided at the end portions with inwardly extending flanges 7 formed integral with the body portion of the heel plate and arranged 60 in flush relation with the upper face thereof as clearly illustrated in Fig. 5 of the drawing. The flanges 7 which are relatively thin to enable them to be placed between the lifts and to interlock the body portion with the 65 lower lift of the heel project from the inner edge 5 and are separated by an intervening space or recess 8 to enable the outer lift of the heel to be nailed between the said flanges. The said flanges 7 which are substantially 70 rectangular have straight edges and are provided at their outer edges with extensions 9 forming narrow flanges across the ends of the body portion of the heel plate to interlock the end of the heel plate 75 with the lower or outer lift 10 of the heel. The body portion 1 of the heel plate is also provided with a plurality of perforations 11 adapted to receive fastening devices for securing the heel plate to the heel 4. These 80 fastening devices may be of any desired character and any preferred number may be employed, it being desired to provide perforations at the ends of the body portion and in some instances at the center thereof 85 as shown in Fig. 4. The spaced end flanges form a recess which is entirely open at the inner side of the heel plate to interlock the said flanges with the solid portion of the heel and to permit a solid portion to lie between the projecting flanges. Also the open 90 character of the recess greatly facilitates the fitting of the heel plate in position without unnecessary waste of leather or weakening of the heel.

What is claimed is:

A heel plate comprising a substantially oblong body portion of approximately uniform width throughout its entire length curved longitudinally to present a concave 100 inner side edge and a convex outer side edge and provided at the said inner concave side edge with thin flat imperforate flanges projecting inwardly from the ends of the body portion of the heel plate to interlock the 105 same with the heel at such points, and spaced apart throughout their entire length to form an intervening recess to enable the heel to be nailed between the flanges, the recess being entirely open at the ends of the 110 flanges to permit them to engage with a relatively large solid intervening portion of the

heel, said flanges being provided with outer narrow extensions forming end flanges, which extend entirely across the end edges of the body portion of the heel plate from the outer side edge to the inner side edge to interlock the ends of the body portion with the solid contiguous portions of the heel to

prevent the heel plate from rocking or dropping out of flush relation with the heel.

In testimony whereof I affix my signature 10 in presence of a witness.

FRANK FORAMA.
